UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,346,281.

Specification of Letters Patent. Patented July 13, 1920.

Application filed October 10, 1919. Serial No. 329,712.

To all whom it may concern:

Be it known that I, WILLIAM D. THOMPSON, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of the flexible type. In the present state of the art, it is usual in the construction of this type of roofs to employ metallic roofing sheets which are arranged between carlines, 15 the joints being weather-proofed by caps embracing said carlines and upstanding edge flanges on the sheets. This construction necessitates a uniform spacing of the carlines and a width of sheet corresponding 20 to such spacing. It has not, however, been the uniform practice in the past to build car roofs with carlines equally spaced, and frequently, new roofs are applied to these old cars. This necessitates the tearing out 25 of the roof frame of carlines and purlins and the building of a new frame with the carlines uniformly spaced.

It is the object of the present invention to obtain a construction of flexible roof which 30 is applicable to old roof frames irrespective of the spacing, shape, or arrangement of the carlines. It is a further object to obtain various features of advantage, as hereinafter set forth.

35 In the drawings:

Figure 1 is a plan view of the car roof;

Fig. 2 is a cross-section thereof in the plane of one of the mullions;

Fig. 3 is a section longitudinally of the 40 roof;

Fig. 4 is a cross-section through the side plate of the car, showing the manner of securing the weather-proofing cap;

Fig. 5 is an end elevation thereof;

45 Figs. 6 and 7 are views similar to Figs. 2 and 3 showing a modified construction.

Composite wooden and metal car roofs are usually classified as "outside metal roofs" and "inside metal roofs", according to the 50 arrangement of the metal weather-proofing means. In each type there is a roof frame composed of carlines and purlins with a covering of roofing boards nailed thereto. The outside metal roofs are further provided 55 with metal weather-proofing sheets laid on

top of the boards, while the inside metal roofs having metal drip pans or sheets arranged beneath the boards for conducting the water outward to the eaves. When outside metal roofs are repaired, it is frequently necessary not only to replace the metal weather-proofing sheets, but also many or all of the roof boards, and where the latter are not replaced, they are frequently in a warped uneven condition, which interferes 60 greatly with the laying of a smooth outside cover. Also there is danger from old nails coming in contact with the metallic sheets and puncturing the same. I have, therefore, devised a construction free from these 65 objections, which consists essentially in a flexible metallic roof laid directly upon the roof frame. The sheets of this metallic roof are not arranged between carlines, nor are they necessarily of a width corresponding 70 to the spacing of the carlines. Instead, the sheets are laid on the framework irrespective of the spacing of the carlines and are retained in position with sufficient freedom to compensate for the weaving or distortion of the frame, but are limited from 75 abnormal displacement.

In detail, A are carlines and B are purlins arranged thereabove and extending from end to end of the car. C are roofing sheets which 80 are formed with upstanding flanges at their opposite sides, said flanges being preferably return-bent, as indicated at D. There is also a marginal portion E of the sheet, which is raised to a slightly higher plane 85 than the body portion so as to be normally free from contact with the purlins. F are cap members for embracing the return-bent flanges D of adjacent sheets and provided with an oppositely return bent flange G for 90 engagement therewith. The caps F are secured to the car frame, so as to hold the sheets thereupon, but by reason of the open return-bends a limited universal freedom 95 of movement in the plane of the sheets is 100 permitted.

To prevent abnormal displacement of the sheets and to relieve the flanges from stress, there are preferably arranged between the sheets transverse strips or mullions H. 105 These are bolted, or otherwise secured, to the purlins, as indicated at I, and are so positioned as to extend between adjacent sheets and beneath the cap. The mullions are of sufficient length to properly guide the sheets, 110

but instead of extending completely across the roof frame to the side plates thereof, they preferably terminate at the first purlin from the side plate.

5 The sheets C are further provided with upstanding flanges J at the ridge and with down-turned flanges K at the eaves. The latter are further provided with inwardly extending open return-bent portions L for 10 loose engagement with down-turned flashing strips M at the eaves. The caps F are also provided with down-turned flanges N at the eaves, which overlap the flanges K of adjacent sheets and are preferably inturned 15 at their lower edges, as indicated at O. To securely hold the caps upon the roof frame they are attached preferably to bracket members P secured to the inner side of the plate Q by suitable means, such as the lag screws 20 P' and bolts P''. The attachment between the brackets P and the caps is one which permits of first telescopically engaging the caps with the roofing sheets upon the frame. As shown, there is secured within the cap 25 member the pressed sheet metal member R which rests upon a strip S secured to the upper face of the plate Q. The member R is riveted, or otherwise secured, to the flange N at N' and also to the top of the cap at T, so as to form a rigid connection therewith. At its inner end the member R has an apertured flange R' which registers with a corresponding aperture in the bracket member P, while the bolt U engaged with the registering apertures pivotally attaches the cap to the frame. At the ridge there is arranged 35 the usual ridge caps V and junction caps W for weather-proofing between the sheets.

Where the roof as above described is to be 40 applied to an old car previously provided with an outside metal or inside metal roof, the roofing boards are first removed and the frame is cleared of projecting nails. The mullions H are then properly positioned 45 upon the frame and are secured thereto by the bolts I. The sheets C are then laid upon purlins intermediate the mullions H, after 50 which the caps F are telescopically engaged with adjacent sheets and slid inward over the mullions. The caps are secured by the 55 bolts U to the brackets P and the ridge portions of the sheets and caps are secured by the ridge caps V and junction caps W. When thus assembled, the roofing sheets are 60 free to play within the space between the mullions and are also free to move endwise within the limits of the open return-bent portions at the eaves and the clearance space within the ridge caps. Abnormal outward 65 displacement is however prevented by the down-turned flanges M of the caps, which overlap the flanges K of the sheets, while the caps themselves are prevented from outward movement by the connecting bolts U.

65 In Figs. 6 and 7 I have shown a modified

construction in which instead of laying the roofing sheets directly upon the purlins, said purlins are provided with facing strips B'. The purpose of these strips is to protect the upper face from any old nails, or other obstructions, which might injure the sheet and to provide a smooth surface for the sheets to rest upon. I also preferably provide an intermediate support X for the sheets which is formed of a strip extending transversely 75 of the car or parallel to the mullions and midway between the same. With such a construction lighter gage metal may be used for the roofing sheets.

What I claim as my invention is:

1. A car roof comprising an open frame of carlines and purlins, roofing sheets laid directly upon said frame irrespective of the spacing of the carlines and having a limited freedom of movement, means secured to 85 the frame between adjacent sheets for limiting the movement thereof, and means embracing said limiting means for weather-proofing and holding down the sheets.

2. In a car roof, a frame of carlines and 90 superposed purlins, roofing sheets laid directly upon said purlins irrespective of the spacing of the carlines and having a limited freedom of movement, members secured to the purlins intermediate adjacent sheets for 95 limiting the movement thereof, and weather-proofing means embracing said members and constituting the holding down means for said sheets.

3. A car roof comprising a frame of carlines and superposed purlins, roofing sheets laid upon said purlins irrespective of the spacing of said carlines, mullions secured to said purlins intermediate adjacent roofing sheets forming stops for limiting movement thereof, and caps embracing said mullions and the edges of adjacent sheets forming a weather-proofing and holding down means therefor.

4. A car roof comprising a frame of carlines and superposed purlins, mullions secured to said purlins irrespective of the spacing of said carlines, roofing sheets laid between mullions with clearance for a limited freedom of movement, the edges of said sheets having return-bent weather-proofing flanges, caps for embracing said mullions having cooperating return-bent flanges telescopically engaging the flanges of the sheets, and means for securing said caps to said frame and thereby holding down said sheets.

5. A car roof comprising a frame of carlines and superposed purlins, mullions secured to said purlins, irrespective of the spacing of the carlines, said mullions terminating short of the side plate of the car, roofing sheets laid upon said purlins intermediate said mullions with freedom for limited movement, caps embracing said mullions and forming a weather-proof tele-

scopic engagement with said sheets, brackets secured to said side plates in alinement with said mullions, and means for securing said caps to said brackets when telescopically engaged with said sheets.

6. A replacement roof for cars designed for board roofs, comprising facing strips laid upon the purlins and secured thereto, mullions mounted upon said facing strips, 10 roofing sheets laid upon said facing strips intermediate said mullions, and weather-proofing means embracing the mullions and engaging the sheets.

7. In a car roof, the combination of an open frame of carlines and purlins, facing 15 strips secured to said purlins, mullions mounted upon said purlins, supporting strips arranged intermediate said mullions and bridging the space between said purlins, roofing sheets laid upon said facing strips 20 and supporting strips, and weather-proofing means embracing said mullions and engaging said sheets.

In testimony whereof I affix my signature.

WILLIAM D. THOMPSON.
